THOMAS SCANTLIN AND JAMES M. SCANTLIN, OF EVANSVILLE, INDIANA.

Letters Patent No. 79,692. dated July 7, 1868.

IMPROVEMENT IN COAL-SCUTTLES.

The Schedule referred to in these Letters Patent and making part of the same.

TO ALL WHOM IT MAY CONCERN:

Be it known that we, THOMAS SCANTLIN and JAMES M. SCANTLIN, of Evansville, in the county of Vanderburg, and State of Indiana, have invented a new and useful Improvement in Coal-Scuttles; and we do hereby declare that the following is a full, clear, and exact description thereof, which will enable others skilled in the art to make and use the same, reference being had to the accompanying drawings, forming part of this specification, in which—

Figure 1 is a central vertical section of our improved scuttle, through the line $z z$ of fig. 2.

Figure 2 is a bottom view of the same.

Similar letters of reference indicate like parts.

The object of this invention is to provide a simple, durable, and superior coal-scuttle, the construction of which is hereinafter set forth.

By reference to the drawings, A is the body of the scuttle, and B the bottom of the same. The body is preferably of sheet iron, though other metal will answer. The bottom is preferably of cast iron, it being formed with a conical rim or flange, over which the lower edge of the body is bent or lapped, as shown at $d d$, fig. 1, thereby dispensing with rivets or other like fastenings.

Four legs, $a a a a$, are cast on the bottom, also the diagonal ribs or feathers, $e e e e$, and at the intersection of these ribs a boss or fifth leg, b , is cast.

The body is formed with a horizontal fluting, as shown at c , fig. 1, which assists the lapped edge to hold the bottom firmly affixed to the body.

The legs $a a a a$ being a continuation of the flange of the bottom, the edge of the bottom does not lap over them, but merely rests against them at that point.

The ribs may be thickened or augmented at the point of their intersection sufficiently to form a point of equal height as the other legs, thereby serving as a fifth leg. This would be an equivalent modification of our invention, without absolutely forming the boss b . The ribs are for the purpose of strengthening the bottom.

Having thus described our invention, we claim as new, and desire to secure by Letters Patent—

A coal-scuttle having the body A formed with a fluting, c , and the edge or border just below this fluting lapped over a conical flange of the bottom, B, the said bottom being formed with legs $a a a a$, b , and ribs $e e e e$, all substantially as described, and for the purpose set forth.

The above specification of our invention signed by us, this 22d day of April, 1868.

THOMAS SCANTLIN,
JAMES M. SCANTLIN.
